UNITED STATES PATENT OFFICE.

ELMER T. MCPHERSON, OF WILMINGTON, OHIO, ASSIGNOR TO THE IRWIN AUGER BIT COMPANY, OF WILMINGTON, OHIO, A CORPORATION OF OHIO.

BIT.

1,299,490.

Specification of Letters Patent.

Patented Apr. 8, 1919.

Application filed May 10, 1918. Serial No. 233,616.

To all whom it may concern:

Be it known that I, ELMER T. MCPHERSON, a citizen of the United States, residing at Wilmington, in the county of Clinton and State 5 of Ohio, have invented certain new and useful Improvements in Bits, of which the following is a specification, reference being had therein to the accompanying drawing:

This invention relates to bits for boring 10 holes in wood, and it is applicable to auger bits, brace bits, machine bits and the like. It comprises an improved construction which is less liable to clog with chips than the forms now in use. In particular the invention comprises a double cutter bit having a single 15 twist shank, and a portion of the twist being cut away opposite one of the cutting edges. Thus a greatly increased space is left for the passage of the chips.

20 In the drawings, Figures 1 and 2 are views of such a bit having spurs and extension lips, and especially adapted to fairly soft wood, these views both being elevations but at different angles; Fig. 3 is a view similar to Fig. 25 1, but showing a bit having a flat head and no spurs and being particularly adapted to use in hard wood; and Fig. 4 shows the old form of bit merely for comparison; Figs. 5 and 6 are end views of Figs. 1 and 4 respectively.

The drawings show bits of the solid center type having the usual shank 1 and solid center or stem *a* surrounding which is the twist 2 integral with the stem. In the form of 35 Figs. 1 and 2 the twist ends in a cutter 3 including a spur 4 and an extension lip 5 having a cutting edge 6. Also the stem *a* has integral therewith a second partial twist 7 near the cutting end of the bit, this second 40 twist being provided with a spur 8 and an extension lip 9 ending in a cutting edge 10. The twist 7 is not complete as is the twist 2, it being cut away at the portion 11 immediately at the rear of the spur 8. The different 45 construction thus produced will be evident from comparing Figs. 1 and 2 with the older form of Fig. 4. In Fig. 4 the parts are similarly numbered, but each numeral of Fig. 4 is given the suffix "a" and it will be 50 seen in Fig. 4 that the portion 11^a of the partial twist is carried around to a point adjacent the cutting edge 6^a. In Figs. 1 and 2 on the contrary the twist 7 terminates in a plane from the rear of the spur 8 to the stem 1.

Thus a much larger space is left between the 55 partial twist 7 and the cutting edge 6 than in the form of Fig. 4 and thereby chips pass out more easily and do not clog the bit.

The form of Fig. 3 will be clear from the previous description, the bit of this figure 60 being adapted to hard wood. It has no spurs, but is provided with a cutting edge 12 and a side lip 13 on the partial twist 14. Here also the partial twist is cut away in a plane passing from the rear end of the side lip 13 directly to the stem of the bit. The advantages of the form of Figs. 1 and 2 are found also in the form of Fig. 3. In both the new forms the partial twist terminates directly at the rear of the cutter in a plane reaching directly 70 to the solid center of the bit.

In the ordinary bit, such as is shown in Fig. 4, the angle between the cutting edge 10^a and the plane 11^a at the rear of the cutter is approximately 160° measured around 75 the stem, while in the new forms of Figs. 1 to 3, the corresponding angle is about 80° or somewhat less than a right angle. Also, the pitch of the twist 2 is greater in the new forms than the pitch of the partial twist 7, 80 but the pitches of the twists in Fig. 4 are the same. Thus in the forms of Figs. 1 to 3 the twists gradually separate as the plane portion 11 is approached.

These two changes in the construction provide 85 the additional space for the chips to pass as referred to above, and thus prevent the clogging of the bits by the chips.

The two forms of bit shown in Figs. 1 and 3 are to be understood as illustrative only of 90 the invention, it being applicable to any form of bit having a double cutter head with a single twist.

While I have shown and described certain 95 features as constituting my invention, it will be understood that parts have been shown for purposes of illustration only, and that I do not desire to be limited to such details, as obvious modifications will occur to a person skilled in the art.

Having thus fully described my invention, what I claim as new and desire to secure by letters patent, is:—

1. In a bit, a solid center having an integral twist ending in a cutting edge and an 105 integral partial twist also ending in a cutting edge, the partial twist being cut away on a plane substantially at right angles to the

axial plane in which the main cutting edge lies and intersecting said cutting edge at its juncture with its solid center.

2. In a bit, a solid center having an integral twist ending in a cutting edge, and an integral partial twist also ending in a cutting edge, the partial twist being cut away adjacent the cutting edge of the complete twist in a plane substantially at right angles therewith and reaching from the rear of said partial twist to the center of the bit.

3. In a bit, a solid center having an integral twist thereon, said twist ending in an extension lip having a cutting edge and also having a projecting spur, a partial twist on said center near the cutting end of the bit, said partial twist having a similar extension lip ending in a cutting edge and a projecting

spur, the partial twist being cut away directly at the rear of its spur in a plane reaching from said spur to the solid center and substantially at right angles to the cutting edge of the complete twist.

4. In a bit, a solid center having an integral twist thereon ending in a cutting edge and an integral or partial twist also ending in a cutting edge, the partial twist being cut away to provide an angular open space of substantially 90 degrees between the plane of said cut away portion and the axial plane of the cutting edge of the complete twist and extending upwardly between the horizontal plane of said cutting edge and the opposite portion of the complete twist.

In testimony whereof, I affix my signature. 35
ELMER T. McPHERSON.
